(57) **CLAIM**

The ornamental design for a herb cultivator, as shown and described.

DESCRIPTION

FIG. 1 is an isometric view of the herb cultivator with its door closed;

FIG. 2 is an isometric view of the FIG. 1 herb cultivator with its door open;

FIG. 3 is an isometric view of a herb cultivator according to a second embodiment with its door hinged on a side opposite that of the FIG. 1 herb cultivator;

FIG. 4 is an isometric view of the FIG. 1 herb cultivator with its door open and its lower tray removed;

FIG. 5 is an isometric view of the FIG. 1 herb cultivator with its door open and its upper tray and shelf removed;

FIG. 6 is an isometric view of the FIG. 1 herb cultivator from a rearward perspective;

FIG. 7 is a front elevation view of the FIG. 1 herb cultivator;

FIG. 8 is a rear elevation view of the FIG. 1 herb cultivator;

FIG. 9 is a left side elevation view of the FIG. 1 herb cultivator;

FIG. 10 is a right side elevation view of the FIG. 1 herb cultivator;

FIG. 11 is a top plan view of the FIG. 1 herb cultivator; and,

FIG. 12 is a bottom plan view of the FIG. 1 herb cultivator. The features shown in broken lines are for illustrative purposes only and form no part of the claimed design.
